UNITED STATES PATENT OFFICE

2,184,602

STRIPER

Roscoe C. Miller, Syracuse, N. Y.

Application July 7, 1938, Serial No. 217,986

3 Claims. (Cl. 15—166)

This invention appertains to new and useful improvements in striping means whereby lines can be formed on china and other surfaces in a quick and efficient manner.

5 The principal object of the present invention is to provide a striper whereby a plurality of lines can be formed simultaneously without any increased effort on the part of the person handling the device.

10 Another important object of the invention is to provide a striper especially adapted for striping china and other articles capable of taking stripes wherein construction is provided whereby a plurality of stripes can be formed simultaneously and 15 wherein the construction is such as to permit adjustment to increase or decrease the spaces between the stripes.

These and various other important objects and 20 advantages of the invention will become apparent to the reader of the following specification.

In the drawings:

Figure 1 represents a perspective view of the implement in compact form.

Figure 2 is a plan view of the instrument in 25 expanded form.

Figure 3 is a plan view of the implement partly contracted.

Figure 4 is a section on line 4—4 of Figure 2.

Figure 5 is a sectional view taken substantially 30 on line 5—5 of Figure 4.

Figure 6 is a perspective view of one of the brush units.

Figure 7 is a cross sectional view.

Referring to the drawings wherein like numbers 35 designate like parts, it can be seen that obviously more than three striper units can be employed but for the purpose of illustration three units are shown in the drawings. Each unit is constructed substantially identical with the others. The units consist of the L-shaped blocks 5, 6 and 7. From the upper portion of the block 5 extends the tubes 8 and 8a, while from the upper portions of the block 6 extends the somewhat longer and smaller diameter tubes 9 and 9a, these extending through the tubes 8 and 8a respectively. Extending from the upper portion of the block 7 are the elongated rods 10 and 10a which extend through the tubes 8 and 8a, and also through the tubes 9 and 9a.

50 A lug 11 is provided on the block 7 and a pin hook 12 is provided on the tube 8a and between this lug 11 and the pin hook 12 is the coiled extensible spring 13 which serves to hold the units in compact relation as shown in Figure 1. A handle 14 extends from the block 5.

Each block accommodates a striper unit 15. Each of these units consists of a bristle holder 16 from which the bristles a extend and a cylindrical structure 17 connected by the neck 18 to the holder 16. The cylinder 17 is provided with a conical-shaped opening extending longitudinally therein and is slotted as at 19. The conical opening in the cylinder 17 is threaded to accommodate the conical-shaped screw 20 which has the screw driver receiving kerf 21 in its large end. A bore 22 extends through the block 5, 6 or 7, receiving the cylinder 17. One end of this bore 22 is threaded as denoted by numeral 23 to receive the handle 14.

Obviously the units 5, 6 and 7 can be spaced 15 away from each other to any extent desired and held by the fingers of the operator's hand while the striper is in use.

While the foregoing specification describes the invention in specific terms, it is to be understood 20 that numerous changes in the shape, size and materials may be resorted to without departing from the spirit and scope of the invention as claimed hereinafter.

Having described the invention what is claimed 25 as new is:

1. A striper comprising a plurality of brush-carrying units and means whereby the units can be adjusted to laterally spaced intervals, said means comprising tubes extending laterally from 30 certain of the units and a rod extending from one end unit, said tubes and rod being disposed in telescopic relation.

2. A striper comprising a plurality of brush-carrying units and means whereby the units can be adjusted to laterally spaced intervals, said means comprising tubes extending laterally from 35 certain of the units and a rod extending from one end unit, said tubes and rod being disposed in telescopic relation, and an extensible coiled 40 spring having one end connected to the outer end portion of the tube of one end unit and having its opposite end connected to the other end unit for tending to urge the said units into contracted relation.

3. A striper comprising a plurality of brush-carrying units, each of the said units comprising a block and a brush element, each of the brush elements being provided with a split hollow shell 50 adapted to be disposed into a block and a tapered member in the block adapted to be advanced into the said shell to bind the same against the inner side of the block.
